Primary Examiner — Randall H Gholson(74) *Attorney, Agent, or Firm* — ARC IP Law, PC; Joseph J. Mayo(57) **CLAIM**

The ornamental design for a sleeve for cable connector, as shown and described.

DESCRIPTION

FIG. 1 is an upper perspective view of a sleeve for cable connector.

FIG. 2 is a front view of the sleeve for cable connector.

FIG. 3 is a back view of the sleeve for cable connector.

FIG. 4 is a left side view of the sleeve for cable connector.

FIG. 5 is a right side view of the sleeve for cable connector.

FIG. 6 is a top view of the sleeve for cable connector; and,

FIG. 7 is a bottom view of the sleeve for cable connector.

The broken lines in the drawings show unclaimed features of the sleeve for cable connector and form no part of the claimed design.
